UNITED STATES PATENT OFFICE.

JONATHAN CREAGER, OF CINCINNATI, OHIO.

BRICK-MACHINE.

SPECIFICATION forming part of Letters Patent No. 284,949, dated September 11, 1883.

Application filed April 12, 1883 (No model.)

To all whom it may concern:

Be it known that I, JONATHAN CREAGER, a citizen of the United States, residing at Cincinnati, in the county of Hamilton and State 5 of Ohio, have invented certain new and useful Improvements in Brick-Machines, of which the following is a specification, reference being had therein to the accompanying drawings.

The first part of my invention relates to those 10 brick-machines which are provided with levers, rock-shafts, and connecting-rods for advancing and retracting the horizontally-reciprocating followers that force the filled molds out at the lower part of the pug-mill; and the 15 improvement consists in journaling the main lever of such machines in a fulcrum bearing or box capable of shifting automatically the instant the follower or mold is arrested either with a stone or other obstruction, thereby rendering said main lever inoperative for the time being. This automatically-shiftable fulcrum-bearing is maintained in its normal position with a trip-lever provided with a weight or poise, which can be adjusted to prevent any 20 sliding of said bearing until a certain predetermined resistance has been overcome.

The second part of my invention consists of a novel combination of devices wherewith the shiftable fulcrum-bearing is held in check by 25 the heel of the trip-lever, and yet is capable of disengaging itself therefrom when occasion may require.

The third part of my invention consists in providing the machine with a self-acting catch 30 which retains the trip-lever in the elevated position it assumes in the act of liberating the fulcrum-bearing and allowing it to slide.

The fourth part of my invention consists in combining a counter-lever and suitable connections with the trip-lever, in order that the latter may be operated by the attendant who feeds the empty molds into the machine, thereby enabling said attendant to arrest the action of the main lever at any time.

The fifth part of my invention comprises a 45 novel bumping or jarring apparatus, said device being an improvement on the construction seen in the patent granted to me May 9, 1882.

The sixth part of my invention consists in a 50 novel appliance for lubricating the step of the pug-mill shaft.

The seventh part of my invention consists in furnishing the follower with peculiarly-constricted journal-bearings that confine said follower to the track upon which it runs.

55

In the annexed drawings, Figure 1 is a side elevation of my improved brick-machine, the main lever being shifted so as to advance the follower. Fig. 2 is an elevation of the lower portion of the opposite side of the machine. Fig. 3 is an elevation of that end of the frame to which the bumper or jarring apparatus is applied. Fig. 4 shows the counter-lever and its connections. Fig. 5 is an enlarged elevation of one of the bumper-blocks. Fig. 6 is an axial section of the step of the pug-mill shaft and its accessories. Fig. 7 is a sectionized plan of the drum around which is coiled the chain that connects said drum with the shiftable fulcrum-bearing. Fig. 8 is a vertical section, showing the self-acting catch engaged under the elevated trip-lever. Fig. 9 is an enlarged sectional elevation of the shiftable fulcrum-bearing and its immediate accessories. Fig. 10 is a horizontal section of said bearing, taken in the plane of the pivot. Fig. 11 is a transverse section thereof. Fig. 12 is a sectional elevation of the trip-lever heel and its accessories. Fig. 13 is a vertical section through one of the journal-bearings of the follower.

8c

A represents the frame-work, and *a* the pug-mill, of an ordinary brick-machine, said frame having at top a driving-shaft provided with a pinion indicated by the dotted lines *a'*, which pinion gears with the master-wheel *B* of counter-shaft *b*. This shaft *b* communicates motion by suitable bevel-gearing to the pug-mill shaft *X*. (Seen in Fig. 6.) Wheel *B* has a stud-shaft, *b'*, upon which latter is journaled a roller, *B'*, adapted to operate against the upper end of a main lever, *C*, said lever being pivoted at *c* to a fulcrum bearing or box, *D*. As shown in Fig. 11, the base of this box flares outwardly, but is capable of sliding freely in the longitudinal slot of a guide, *E*, the latter being securely bolted to one of the side timbers, *a''*, of the frame. Furthermore, one end of this fixed guide has a head, *e*, perforated at *e'*, through which hole plays freely a rod, *F*, screw-threaded at its opposite ends, *f'f'*, as seen in Fig. 9. Thread *f'* engages with a shackle or swivel, *g*, while the thread *f* has screwed upon

it three nuts, G G' G''. (Seen in Fig. 10.) The nuts G G' secure rod F to the box D, and the nut G'' serves as an adjustable stop that limits the travel of said box or bearing toward the head e. Swivel g has attached to it one end of a chain, H, whose other end is fastened to a lug, i, of drum I, which latter is journaled on a stud-shaft, j, projecting laterally from a plate, J, bolted to the frame A, the details of said drum, &c., being more clearly seen in Fig. 7. Furthermore, plate J has a hook, j', adapted to bear against a collar, K, cast on the inner end of drum I, said collar being cut away at k to clear the hook j' when the drum is first slipped onto the shaft j. The drum being then slightly turned, the hook prevents it accidentally working off of said shaft. Projecting from the outer end of the drum is a spur, i', adapted to bear upon a tail-piece, L, as more clearly seen in Fig. 12, a bolt, l, and slot l' enabling said tail-piece to be adjusted longitudinally of the shoe M, which latter is pivoted at m to a hanger, m', attached to the beam a''. This shoe protects the heel of a trip-lever, N, hung on pivot m, and provided with an adjustable weight, n. Attached to the long arm of this lever is a connection, n', communicating with one end of a counter-lever, N', (seen in Fig. 4,) said lever being pivoted to the frame at N'', and having a pull or handle, n'', convenient to the attendant who feeds the empty molds into the machine. (See Fig. 2.) Trip-lever N is adapted to play vertically in the slot o of a bracket, O, attached to beam a'', said bracket being further slotted at o' to admit a pivoted bell-crank, o'', which serves as a self-acting catch to arrest said lever in its elevated position, as seen in Fig. 8.

Attached to the lower end of main lever C is a link, d, that takes hold of an arm, p, of rock-shaft P, the longer arms of which, p' p'', have coupled to them connecting-rods Q Q'. These rods are united to studs u of follower U, one of said studs being seen in Fig. 13. Furthermore, this rock-shaft P is provided with a pair of cranks, R R', weighted, respectively, at r r', for the purpose of retracting follower U as soon as roller B' escapes from the upper end of main lever C.

Attached to the beams a'', upon which runs the follower U, are hangers a''', that afford journal-bearings for two frames, S S', adapted to swing transversely of said beams, these frames being furnished at their upper ends with blocks s s', so arranged as to strike alternately the opposite ends of the mold indicated with dotted lines in Fig. 3. The lower ends of frames S S' are loaded at s'', and are united with a connecting-rod, s''. This rod may be made in two sections, having right and left hand threads to engage with a swivel-nut, in order that the frames S S' may be adjusted toward or away from each other, as occasion may require. s''' is the operating-lever of said swinging frames. Journaled in the main frame is a roller, T, that facilitates the inser-

tion of the empty molds in advance of the follower U. (See Fig. 2.) Secured to the inner side of said follower is a casting, V, that serves as the journal-bearing for the shaft W of roller w, that runs on the track w', attached to beam a'', as seen in Fig. 13. This casting has at top an oil-channel, v, and near the bottom a rib or flange, v', that bears against the under margin of track w', and thereby prevents canting of the follower. Of course the opposite side beam of said follower must have a similar ribbed casting. The shaft X of the pug-mill (seen in Fig. 6) has a spindle, x, adapted to revolve in a bearing in the step Y, an oil-chamber, y, being formed in said step, which chamber is supplied with lubricant by a small pipe, Z, tapped into the lower blade, z, of said shaft.

Preparatory to operating the machine the weight n is adjusted along the trip-lever N, according to the nature of the clay that is to be converted into bricks. If the clay is very stiff, the weight is placed near the extreme end of the lever; but if the clay is loose and friable, said weight is set much nearer the bracket O. Power being then applied to the machine, so as to revolve the master-wheel B in the direction of the arrow seen in Fig. 1, the main lever C swings on its pivot e, thereby advancing the follower U and forcing the charged mold out of the press-box in the usual manner. As soon, however, as roller B' escapes from contact with main lever C, the weights r r' restore said lever and follower to their normal positions, so as to allow an empty mold to be inserted in advance of said follower, the roller T enabling the most convenient application of the mold. These operations are repeated at each and every stroke of lever C, the weight n retaining the trip-lever N in its normal position, and thereby preventing any rotation of drum I. Consequently the sliding bearing D remains immovably in its guide E; but the very moment any unusual strain is imposed on the machine—as, for example, by a stone or other obstruction getting wedged in the mold—such strain is at once transferred to the heel of trip-lever M by means of chain H, drum I, and spur i'. This strain then overcomes the resistance of weight n, and lever N is at once tripped so far as to allow spur i' to escape from contact with the tail-piece L, which act leaves the drum I free to revolve on shaft j and permits fulcrum-bearing D to recede from said drum. This automatic shifting of said bearing at once arrests the action of lever C and effectually prevents breakage of any of the operative parts of the mechanism. As soon as the lever N is thus tripped, the bell-crank catch o'' swings out from the slot o', as seen in Fig. 8, and locks said lever in this position until said catch is intentionally forced back. The lever then falls and rests on the shorter arm of the bell-crank. Again, in case one of the molds should lodge in the act of being fed in over the roller

T, the attendant can instantly pull on handle n'' , thereby lifting the lever N and tripping off the spur i' , so as to shift the bearing D. It will thus be seen that said trip-lever is capable of working either automatically or by hand, as occasion may require, and in either event it instantly arrests the action of the machine. As rapidly as the charged molds reach the end of beams a''' they are jarred by causing the blocks $s s'$ to strike against the opposite ends of said molds. This striking action is effected by the attendant grasping the handle s''' and vibrating it from right to left, the weights s'' causing the blocks $s s'$ to strike the mold with sharp, quick blows, that at once loosen the compressed clay. The connecting-rod s'' draws the lower ends of frames S S' toward each other, thereby keeping the weights s'' under the frame, where they will not interfere with the operator. As the pipe Z is carried up to the top of the pug-mill, it is evident the shaft-steps Y y can be lubricated at any time and without taking the machine apart. In a modification of my invention the trip-lever N can be omitted and the fulcrum-bearing D be held in check either with a spring or weight; but the trip-lever is preferred. Finally, the tail-piece L can be swung up toward hanger m' , preparatory to re-engaging the spur i' with the trip-lever heel.

I claim as my invention—

1. The combination, in a brick-machine, of an automatically-shiftable fulcrum-bearing for the main lever, and a trip-lever carrying an adjustable weight, for the purpose specified.
2. The combination, in a brick-machine, of an automatically-shiftable fulcrum-bearing for the main lever, a trip-lever carrying an adjustable weight, and a self-acting catch that locks said trip-lever in its elevated position, as herein described.
3. The combination, in a brick-machine, of an automatically-shiftable fulcrum-bearing for the main lever, a trip-lever carrying an adjustable weight, a self-acting catch for locking

said trip-lever, and a counter-lever and connections, wherewith the feeder is enabled to operate the trip-lever, for the purpose specified.

50

4. The combination of pivoted main lever C c, shiftable fulcrum-bearing D, fixed guide E e e', swivel g, screw-threaded rod F f', nuts G G' G'', chain H, drum I i, and spur i' , which latter bears on the heel of trip-lever N, 55 for the purpose specified.

5. The combination of drum I, spur i' , adjustable tail-piece L l l', shoe M, and weighted lever N n, said shoe and lever being hung on the common pivot m, as described. 60

6. The bracket O, provided with a slot, o, traversed by the trip-lever N, and having another slot, o', within which is pivoted the self-acting bell-crank o'', for the purpose stated.

7. The plate J, having a stud-shaft, j, and hook j', in combination with the drum I, provided with a lug, i, spur i' , and interrupted collar K k, for the object stated. 65

8. The combination of main lever C, link d, rock-shaft P, arms p p' p', weighted crank R r, and connecting-rods Q Q', which latter actuate the follower U, as herein described. 70

9. The jarring apparatus consisting of the connected swinging frames S S', provided at their upper ends with bumpers $s s'$, and carrying at their lower ends weights s'' , for the object stated. 75

10. The combination, in a brick-machine, of pug-mill shaft X x, chambered steps Y y, and pipe Z, which latter is tapped into the lower blade, z, of said shaft, for the purpose stated. 80

11. The journal-bearing V for follower U, said bearing having a rib, v', that slides under the track w', upon which latter runs the wheel w of said follower, as described. 85

In testimony whereof I affix my signature in presence of two witnesses.

JONATHAN CREAGER.
